UNITED STATES PATENT OFFICE.

EDWARD D. MILLHOUSE, OF PERU, INDIANA.

CONCRETE-VAULT MOLD.

1,182,782.

Specification of Letters Patent. Patented May 9, 1916.

Application filed June 8, 1912. Serial No. 702,512.

To all whom it may concern:

Be it known that I, EDWARD D. MILLHOUSE, a citizen of the United States, residing at Peru, Miami county, and State of Indiana, have invented and discovered certain new and useful Improvements in Concrete-Vault Molds, of which the following is a specification.

My said invention consists in certain improvements in the details of construction and arrangement of parts of steel molds designed especially for forming burial vaults, whereby certain advantages and improved results are secured in the operation of the apparatus, and in the product, all as will be hereinafter more fully described and claimed.

Referring to the accompanying drawings which are made a part hereof and on which similar reference characters indicate similar parts, Figure 1 is a top or plan view of the portion of the vault mold for forming the body of the vault, adjusted and in position for use, the central portion being broken out in order to show the structure on an enlarged scale, Fig. 2 a side elevation thereof, Fig. 3 a longitudinal section on the dotted line 3—3 in Fig. 1, Fig. 4 an end elevation, the central portion being broken away, Fig. 5 a cross section on the dotted line 5—5 in Fig. 1, Figs. 6, 7, 8, 9, 10, and 11, detailed views illustrating a means for clamping and securing the mold sections together at the corners, Fig. 12 a side elevation of the mold section for forming the lid of the vault, Fig. 13 a top or plan view thereof, Fig. 14 a longitudinal section on the dotted line 14—14 in Fig. 13, Fig. 15 a partial end elevational view, Fig. 16 a cross section on the dotted line 16—16 in Figs. 13 and 14, Fig. 17 a detail view, and Fig. 18 a cross section through a vault illustrating the form of vault which my improved mold is designed to make.

In said drawings, like reference characters indicate corresponding parts throughout the several figures thereof.

The body of the vault is formed by the mold illustrated in Figs. 1 to 11 inclusive, said mold consisting of an outside structure, a core, and means for adjusting the parts in relation to each other.

The outer structure comprises two end sections 10, and two side sections 11, each

of which is preferably composed of sheet 55 steel formed with out-turned horizontal flanges on their upper and lower edges and with a recess α midway the height of each section of an appropriate cross-sectional shape to form the external ledge α^1 on the 60 exterior of the body portion A of the vault as illustrated in Fig. 18. At intervals around said sections, vertical braces 12 are interposed between the upper and lower flanges of said central sections, being riveted 65 thereto and formed of angle iron as indicated.

On the top flange at one end of each end section 10 a clamping bolt supporting clip 13 is riveted, having two branches 14 and 70 15, spaced apart, and provided with apertures in line with each other for receiving and supporting the clamping and securing bolts 16. One end of each section 11 is also provided with corresponding supporting 75 clips 13 riveted to the top flange thereof. A series of holes 17 are formed in the top flange of the respective sections 10 and 11 adjacent to the ends of the other sections carrying said supporting clips 13. Said 80 perforations 17 are formed normally slightly to one side of, or out of line with, the perforations in the branches 14 and 15 of the clips 13. The pins 16 are formed tapered on one side as best illustrated in Fig. 6, so 85 that the point will extend into the perforations 17 while said perforation overlaps the holes in section 14 and 15 but slightly. As the pin is then forced to position from that shown in Fig. 6 to that shown in Fig. 8, the 90 corner joint between said sections 10 and 11 will be tightly drawn and secured together. The two part clips afford a support for the pins of sufficient bearing to hold said pins in vertical line and secure the drawing 95 action.

At the lower corners an ear 18 is riveted to one end of each section which is adapted to project through a corresponding slot 19 in the adjacent part. A tapered pin 20 is 100 adapted to project through the perforation in said ears and when driven in is adapted to draw the lower corners tightly together and secure them in place. The slots 19 in the lower corners correspond in position to 105 the holes 17 in the upper flanges and by withdrawing the pins 16 and 20 and adjusting the diagonally opposite corners of the

structure, any width or length of the structure can be secured, as will be readily understood.

The core of the mold is also formed of sheet steel of the form desired with inturned flanges on their top and bottom edges and consists of corner sections 21, end telescoping sections 22 and side telescoping sections 23. Angle bar braces 29 are riveted between the top and bottom flanges. A series of holes 24 are formed through the top and bottom flanges of said overlapping sections and vertical rods 25 are inserted through said holes to secure said several parts together. As will be seen by adjusting the rods 25 from one set of holes to another, the ends of the core can be shortened or lengthened as desired and the sides can be likewise lengthened or shortened as desired to adjust said core to correspond with the size of the vault, which it is desired to form.

The core sections are formed of a less height than the outside sections as best shown in Figs. 3 and 5 and the core after put in position is supported on the top of the outside structure by means of cross bars 26 which are bolted to the flanges of the core and have ends which project beyond the top of said outside structure. In practice the concrete of which the bottom of the vault is made is first deposited within the outside structure to a depth approximately the distance representing the difference in height between the outside structure and the core. The core is then placed in position within the outside structure and the space between the core and the outside filled with concrete and tamped in place and allowed to set, when the various sections composing both the outside structure and the core are separated by removing the holding pins and rods and the finished body of the vault is formed.

Telescopic brace bars 27 are mounted on the flanges of the core, both top and bottom being secured by the rods 25 which pass through perforations therein and together with the supporting bars 26 serve to hold the sides of the core very rigid and insure an even thickness in the walls of the vault. Said bars are adjustable by a series of holes in their overlapping ends and a pin 28 inserted therein.

The top or lid of the vault is formed by the mold sections comprising outside end bars 30 and side bars 31 mounted and secured together in a manner substantially the same as that described for sections 10 and 11 of the body mold, except that in lieu of the double bearing clips 13, for the holding pins 16, blocks 32 are secured on the under face of the flanges of the several sections where required to form a length of bearing sufficient for the purpose. The lower corners are secured by interlocking ears 33 and

slots 34 secured by tapered pins 35 as described for the structure of the body mold. The pins 37 for securing the upper corners are also tapered and the apertures in the one part slightly overhang those in the other 70 part with which said pins engage to secure the drawing or clamping action at each corner.

The core of the mold for the vault top consists of a corner sections 40, telescoping 75 end sections 41 and telescoping side sections 42. As in the structure of the core for the body mold so in the structure of the core of the top mold, a series of registering perforations 43 are formed in the flanges and securing bolts 44 are used in making the adjustments to form a mold of the size desired. The end sections 30 are of a considerably greater height than the side sections 31, in order to provide for the arch formation of 80 the vault top. Said arch is provided for in the structure of the core by cross bars 45 which rest at intervals on the top of the inturned flanges of the side and corner sections and support a top composed of several 90 steel plates as shown. The end plates 47 have flanges covering the ends and extend toward each end of the core for a considerable distance but not far enough to overlap when adjusted to its shortest length. Central plates 48 are mounted on said end plates overlapping the ends of the plates on both ends and also overlapping in the middle as do the end plates 47. By this means the arch of the top of the vault may 100 be formed with the same set of mold plates of any length or width desired, it merely being necessary to overlap their edges more or less according to the size of the mold and the work. In order to stiffen the sides and 105 ends of said core, brace bars 50 are mounted in recesses in the back edge of vertical supports or braces 51, said brace bars being formed of angle-iron and with the edge of their horizontal angle engaging in a notch 110 in the ends of said braces 51, as best shown in Figs. 14 and 15, forming an interlocking brace which affords a very rigid support for the central portion both of the sides and ends of said core. By this means the walls 115 of the top as well as the body of the structure are made of uniform thickness and true, insuring a good fit and avoiding trouble in setting.

Having thus fully described my said invention what I claim as new and desire to secure by Letters Patent is:

1. A sectional vault mold constructed of metal comprising a rectangular outer frame formed of plates with outwardly turned 125 flanges along the upper and lower edges, vertically disposed angular braces secured to the outer sides of the plates at intervals along the length thereof, devices for adjustably connecting together the side and end 130

plates of the frame, an inner rectangular frame constructed of adjustably assembled metal sections, and members for centrally positioning said inner frame within the outer frame, substantially as set forth.

- 5 2. A sectional vault mold constructed of metal comprising a rectangular outer frame formed of plates with outwardly turned flanges along the upper and lower edges, 10 vertically disposed angular braces secured to the outer sides of the plates at intervals along the length thereof, said sections having at their respective ends each a series of apertures in the flanges and a pin supporting member, tapering pins mounted on said supporting members and adapted to engage within the apertures of their respective adjacent sections for drawing the sections together and securing the same with a tight 15 20 fit, an inner rectangular frame constructed of adjustably assembled metal sections, and members for centrally positioning said inner frame within the outer frame, substantially as set forth.

- 25 3. A sectional vault mold constructed of

metal comprising a rectangular inner frame formed of right angular corner sections, end sections and side sections, said sections having inturned flanges along the upper and lower edges thereof telescopically assembling the same, adjustably connected bars mounted on the flanges of said side sections, rods passing through said bars and the flanges of said side sections forming a rigidly connected structure, bars passing 30 through the flanges of said end and corner sections forming connections therebetween, an outer rectangular frame, and a pair of angle bars adjustably mounted on the upper flanges of the inner frame and supporting 35 said inner frame on and centrally within said outer frame, substantially as set forth.

In witness whereof, I have hereunto set my hand and seal at Indianapolis, Marion county, Indiana this 21st day of May, A. D. 40 nineteen hundred and twelve.

EDWARD D. MILLHOUSE. [L. S.]
